(57) **CLAIM**

The ornamental design for a injector, in particular for spray coating devices, as shown and described.

DESCRIPTION

FIG. 1 is a perspective view;

FIG. 2 is a front elevational view;

FIG. 3 is a bottom plan view;

FIG. 4 is a top plan view;

FIG. 5 is a right end view; and,

FIG. 6 is a left end view.

The broken lines shown in the Figures represent portions of the injector, in particular for spray coating devices that form no part of the claimed design.
